UNITED STATES PATENT OFFICE.

JAMES WALBER, OF VINELAND, NEW JERSEY, ASSIGNOR OF ONE-HALF TO
D. D. LUCAS, OF SAME PLACE.

NON-REFILLING BOTTLE.

SPECIFICATION forming part of Letters Patent No. 656,148, dated August 14, 1900.

Application filed October 19, 1899. Serial No. 734,048. (No model.)

To all whom it may concern:

Be it known that I, JAMES WALBER, a citizen of the United States, residing at Vineland, in the county of Cumberland and State of New Jersey, have invented a certain new and useful Improvement in Non-Refilling Bottles, of which the following is a specification.

My invention relates to a new and useful improvement in non-refilling bottles, and has for its object to provide an exceedingly simple and effective construction which will permit the bottle to be filled but once and when so filled will allow the contents to be withdrawn therefrom as occasion may require and yet at all times remain sealed against any attempt to force liquid therein.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a section of a portion of a bottle, showing my improvements embodied therein; Fig. 2, a similar view showing the bottle tilted for the withdrawal of its contents; Fig. 3, a section at the line $\alpha\alpha$ of the stopper in Fig. 1 looking in the direction of the arrow; Fig. 4, a bottom plan of the valve; and Fig. 5, a perspective of the stopper, clearly showing the passage-ways therethrough for the outflow of the contents of the bottle.

In carrying out my invention as here embodied, A represents the bottle, and B the neck thereof, which latter is formed, as shown, flaring upward from its juncture with the bottle, so as to produce an enlarged mouth. Within the neck is formed a conical valve-seat B', and located therein is the valve C, consisting of a body adapted to snugly fit against the conical seat and having the depending wings D, which serve to hold the valve in its proper position within the reduced portion B² of the neck and guide it in its movements. A keeper E, which is adapted to fit within the mouth of the neck, is formed

of a single piece of glass or other refractory material which cannot be drilled or cut without breaking, and this keeper has a central opening F, which leads to the hollow interior 55 thereof, from which the passages G lead to the neck, and this arrangement, as will be readily understood, prevents the insertion of a wire or other implement to a depth sufficient to interfere with the working of the 60 valve, and in practice I prefer that the bottom of the keeper shall be connected with the remainder thereof upon a fragile line, as indicated at H, so that any tampering therewith will tend to break this fragile bottom, 65 which acts as a shield, which of course would render the bottle useless and indicate to the most casual observer that it had been tampered with.

In practice the bottle is first filled, the 70 valve placed therein, and the keeper firmly secured within the mouth by any suitable cement which cannot be loosened without injuring the bottle, after which a cork may be forced within the opening F, thus sealing 75 the bottle for shipment or storage.

When the bottle is to be used, the cork is drawn in the usual manner and the contents thereof may be withdrawn as desired by simply tipping the bottle in the usual manner, 80 which process will cause the valve to leave its seat and come in contact with the under side of the keeper, thus leaving a passage, as indicated by the arrows in Fig. 2, for the outflowing of the liquid. The righting of the 85 bottle will cause the valve to be reseated, and thus securely seal it against the possibility of the inflow of liquid under whatever pressure.

In order that the bottle may not be refilled 90 by submerging it in an inverted position, the valve may be made of such material as will float, or it may be hollow, so as to be buoyant, in which case were the bottle submerged the valve would float upward and be seated in 95 advance of the liquid, thus shutting off the inflowing thereof.

It is a well-known fact that the goods of certain manufacturers are imitated and imposed upon the public in the original bottles 100 and under the original trade-mark, which not only imposes upon the public by inducing

them to purchase spurious goods, but also injures the reputation of the owner of the trade-mark and bottles, as well as depriving him of his just profit; but this will be impossible when my bottle is used, since when it is once filled and the contents withdrawn therefrom it cannot be refilled, thereby serving both as a protection to the manufacturer and the purchasing public.

- 10 One of the principal advantages of my invention is its exceeding simplicity and the fact that no projection or obstruction is formed in the neck of the bottle, and therefore the cost of manufacture is not increased, while 15 at the same time the outflow of the liquid is not interfered with, as is invariably the case when complicated constructions are utilized for such purposes, it being noted that the valve-seat is formed on the interior walls of 20 the neck of the bottle. On account of the neck being flared outward it will tend to facilitate the outward flow of the liquid.

Having thus fully described my invention, what I claim as new and useful is—

In combination with a bottle having a valve-seat formed integral with its thickened and upwardly-flared neck, a valve, having depending guide-wings, adapted to fit snugly in said valve-seat and having a conical recess in its top, a hollow keeper adapted to fit in the mouth of said bottle, having a central opening leading to the interior of said keeper and passages from the interior of said keeper to the neck, lugs on said keeper and a readily-refrangible conical base or shield depending from the lugs and adapted to fit in a recess of the upper surface of the valve.

In testimony whereof I have hereunto affixed my signature in the presence of two subscribing witnesses.

JAMES WALBER.
